UNITED STATES PATENT OFFICE.

CARL BENNETT JEWELL, OF LA JUNTA, COLORADO.

MEANS FOR CLOSING AN OPEN TELEGRAPH-CIRCUIT AT A DISTANT KEY.

No. 908,868.

Specification of Letters Patent.

Patented Jan. 5, 1909.

Application filed March 14, 1908. Serial No. 421,004.

To all whom it may concern:

Be it known that I, CARL BENNETT JEWELL, a citizen of the United States, and a resident of La Junta, in the county of Otero and State of Colorado, have made certain new and useful Improvements in Means for Closing an Open Telegraph-Circuit at a Distant Key, of which the following is a specification.

The object of my invention is to avoid the loss of time and extra labor that is required to run down "opens" on a simplex telegraph circuit, 99% of which are caused by the careless manner in which the operator regards his key, resulting in the inadvertent leaving of the same open and the temporary disabling of the line. On long circuits where there are 30 or 40 offices there is always considerable time lost in running down these "opens"—time lost not only on the open wire but on the wire used for the testing purpose. My invention is designed to avoid this so that the circuit can be closed immediately after the wire opens. Under the present system, if the wire opens it will take the wire chief any

25 where from 15 minutes to one hour to run the trouble down and get the key closed, the wire in the meantime being out of commission.

The advantages of my invention will be especially appreciated by train despatchers 30 who by the nature of things are badly handicapped if they lose their wire for any length of time. They can with my invention close the circuit at their own free will without having to notify the wire chief, or wait for a certain time to elapse so that any clock arrangement will have time to do its work. The important value of my invention is to correct the difficulty promptly as the clock works or the wire chief may be just a minute too late. 35 On branch lines where there is only one wire it will be a trouble saver.

The main feature of my invention consists in the provision at a terminal office of an extra switch and circuit, and an extra battery of such higher voltage than the ordinary working batteries that when the battery of higher voltage is switched on to the line wire, it will force its current through the resistance around any open key and, by working the 45 relay of that key, apprise the forgetful operator at that station that he has left his key open and thus instruct him to close it.

In the drawing—Figure 1 is a diagrammatic view of a simplex telegraph line with

my invention applied to the same, the line 55 being closed through closed keys. Fig. 2 is a similar view with the key K² at a middle station open and the line thereby rendered inoperative, and Fig. 3 is a similar view showing the middle key K² open but with the line 60 closed and operative through the agency of my invention.

In all three figures of the drawing the three stations A, B, C, are similarly equipped and with the terminal batteries marked 25 V 65 constitute an ordinary simplex telegraph, in which a resistance at each station, marked 3700 ohms, is bridged around the key and which resistance, when the key is open, ordinarily affords a sufficient check 70 to the flow of the current to permit the release of the armature of the relay of that station. My invention provides the additional battery of high voltage shown in the right of each figure and marked 150 V and a 75 switch S by means of which either the small battery, 25 V or the large battery 150 V may be thrown on to the line.

Referring now to Fig. 1, this view shows the normal condition of a simplex circuit 80 when all the keys are closed and the circuit is closed. The length of the line shown is 30 miles. Station "A" and "C" are the battery ends of the line.

The line wire has a resistance of 85
25 ohms to the mile making the total resistance of the line -----

Each of the three stations "A", 90
"B" and "C" has one 150 ohm relay, making the total relay resistance -----

The switch "S" is turned to the extreme left in this view which puts 25 volts to the line which is met by 25 volts from the other terminus, making a total of 50 volts, each cell having an internal resistance of 2 ohms the total internal resistance -----

Total ----- 1,300 "

$$50 \text{ volts} \times 1000 = 500 \\ 1000 = 13 \text{ } \frac{500}{39} \text{ mil-amperes}$$

$$\frac{110}{39} \\ \frac{104}{6}$$

750 ohms

According to Ohm's law we have $38\frac{1}{2}$ mil-amperes which is sufficient to work the relays satisfactorily. When the keys are all closed as shown in this view the current will seek the shortest route to the ground, which is through the key and not through the 3,700 ohms in the resistance coil that bridges the key.

Referring now to Fig. 2, this view shows the key K^2 at station "B" open or in the act of making a space.

In this view as in Fig. 1, the line resistance is 750 ohms. The relay resistance 450 " The internal resistance 100 " The contact at the key K^2 at station "B" being broken the current will seek the shortest route to the ground which is through the 3,700 ohms resistance coil that bridges the key K^2 and not through the key, hence the resistance coil is now in the circuit making the added resistance 3,700 "

Total 5,000 " The battery voltage in this instance is the same as in Fig. 1, i. e., fifty volts.

$$\frac{10}{50} \text{ volts} \times \frac{1000}{500 \text{ ohms}} = 10 \text{ mil-amperes.}$$

According to Ohm's law we have 10 mil-amperes which will not work the relay.

Fig. 1 explains that when the key is closed there is a current of $38\frac{1}{2}$ mil-amperes to the line and Fig. 2 explains that when the key is open there is but 10 mil-amperes to the line; hence by simply opening and closing the key we change the current in the line from $38\frac{1}{2}$ mils when closed, to 10 mils when open. When the key is open the resistance coil is thrown in the circuit but when the key is closed again the resistance coil is cut out by reason of a shorter route. When therefore any key at A, B, C, is open the line is inoperative.

Referring now to Fig. 3, this view shows the key K^2 open but the line closed for operative use through the agency of my invention. All that has been necessary to obtain this result was for the wire chief or chief dispatcher to change the position of the lever of switch S from the extreme left to the extreme right, i. e. from a to c. In so doing he has added 125 cells more or 150 cells in all and the total voltage now is 175 volts as follows—

$$\begin{aligned} & 150 \text{ V at "C"} \\ & 25 \text{ V at "A"} \\ \hline & 175 \text{ volts.} \end{aligned}$$

Each cell having an internal resistance of 2 ohms, the total internal resistance

Line	750	"
Relay	450	"
Resistance coil	3700	"

Total	5250	"

$$\frac{175 \text{ volts} \times 1000}{5250 \text{ ohms}} = \frac{100}{9} \text{ mil-amperes.}$$

According to Ohm's law we have $33\frac{1}{3}$ mil-amperes which will work the relays of the circuit satisfactorily until the operator can be told to close his key. The wire can now be worked and the relay at the station where the open occurs is still in an operative circuit and the operator can be called up and told to close his key at the first opportunity, at which time the lever of switch S can be moved back to its normal position at the left.

I claim—

1. The combination with a telegraphic circuit having at its stations relays and keys and resistances bridged across the keys, a source of electro-motive force adjusted in relation to the resistances and relays to release the relay armature when the key is open, by virtue of the resistance; of a separate circuit at the end of the line, a source of electro-motive force arranged within the same larger than the normal working electro-motive force and adjusted in relation to the resistances and relays to operate any relay through the resistance of that station when the key of that station is open.

2. The combination with a telegraphic circuit having at its stations relays and keys and resistances bridged across the keys, a source of electro-motive force adjusted in relation to the resistances and relays to release the relay armature when the key is open, by virtue of the resistance; of a separate circuit at the end of the line, a source of electro-motive force arranged within the same larger than the normal working electro-motive force and adjusted in relation to the resistances and relays to operate any relay through the resistance of that station when the key of that station is open, and means for throwing the excessive electro-motive force on the line.

3. The combination with a telegraphic circuit having at its stations relays and keys and resistances bridged across the keys, a source of electro-motive force adjusted in relation to the resistances and relays to release the relay armature when the key is open, by virtue of the resistance; of a separate circuit at the end of the line, a source of electro-motive force arranged within the same larger than the normal working electro-motive force

and adjusted in relation to the resistances and relays to operate any relay through the resistance of that station when the key of that station is open, and a switch for throwing either the normal working electro-motive force on to the line or the excessive electro-motive force on to the line as desired.

4. The combination with a simplex telegraph embodying keys, relays, resistances bridged across the keys, and normal working

batteries at the end; of a second circuit containing a battery of larger voltage than the normal working battery, said battery of larger voltage being adjusted to operate the relay of any key through its resistance when the key is left open.

CARL BENNETT JEWELL.
